UNITED STATES PATENT OFFICE.

JOHN H. HUNT, OF DAYTON, OHIO, ASSIGNOR, BY MESNE ASSIGNMENTS, TO DELCO-REMY CORPORATION, OF DAYTON, OHIO, A CORPORATION OF DELAWARE.

FUEL BURNER.

Application filed June 4, 1923. Serial No. 643,144.

This invention relates to apparatus for preheating fuel mixtures for use in internal combustion engines, to facilitate the starting thereof, especially in cold weather, and particularly to that type of apparatus which employs an electrically heated coil for igniting the fuel.

One of the objects of the present invention is to provide a protective device in thermal relation with an electrically heated fuel igniting coil, to prevent serious damage to the wire of the coil through over-heating.

Further objects and advantages of the present invention will be apparent from the following description, reference being had to the accompanying drawings, wherein a preferred form of embodiment of the invention is clearly disclosed.

In the accompanying drawing a longitudinal cross section of the device is shown as applied to a heater. This heater comprises the body portion or housing 23, a fragment of which is shown having a passage 152 through which fuel mixture is directed into the combustion chamber 153 of the heater, said housing being provided with a lug 156 passaged to communicate with the combustion chamber 153, the interior of the lug being provided with screw threads 176.

The heating unit comprises a plug or bushing 175 having a screw threaded portion adapted to be screwed into the threaded opening 176 of the housing 23. Bushing 175 is provided with a reduced inner portion having an annular shoulder 177. A fibrous packing 155 is interposed between the shoulder 177 and the annular collar 179 formed on the hollow portion tube or sleeve 178 and a similar collar 155^a is interposed

between said annular shoulder 179 of the porcelain sleeve 178 and the clamping nut 182, said fibrous packing supporting the porcelain tube within the bushing 175. Tube or sleeve 178 extends into the combustion chamber 153 and is provided with upwardly disposed oblique ventilating passages 180 and 181. A hollow clamping nut 182 surrounds the porcelain tube or sleeve 178, said nut being provided with an external threaded portion which is insertible in the threaded portion 184 of bushing 175, the inner end of the nut engaging with the shoulder 183 of said porcelain sleeve 178 to hold said sleeve in position in the bushing 175.

The porcelain sleeve 178 has a longitudi-

dinal passage, the portion 184^a being of lesser diameter than the remaining portion of this passage, thereby providing a shoulder 185. A threaded spool 186 is adapted to fit in the larger diameter passage of the porcelain sleeve 178 resting upon the shoulder 185. This spool 186 is composed of any suitable insulating material, such as soapstone and has a wire 187 wound in the threads provided in the spool so that the wire is flush with the surface of said spool. The wire 187 may be formed of any suitable metal having a relatively high temperature coefficient of resistance, such as iron or nickel, but the total resistance of the wire should normally be less than that of the heating coil 195 provided in the reduced portion 184^a of the longitudinal passage in the porcelain tube. The heating coil is preferably constructed of nichrome wire, one end of said coil being secured to the one end of wire 187 in any suitable manner, while the opposite end of said heating coil 195 is connected with a conducting bracket 196 attached to the bushing 175 so that the point of connection between the heating coil 195 and said bracket lies substantially axially with the combustion chamber 153. The opposite end of wire 187 extends through an axial passage formed in the threaded portion 191 of the terminal cap 190, said wire being in electrical connection with said threaded portion. The terminal cap 190 is provided with a rim 197 which is pressed or spun into the groove 198 formed in the porcelain tube 178 whereby said cap is held securely in position on said tube. Threaded portion 191 of said cap is adapted to receive a suitable terminal connection leading from any suitable source of current supply.

When it is desired to operate the heater any suitable circuit controlling switch, not shown, may be operated to cause current to flow from a source of supply to the terminal cap 190 through wire 187 connected therewith, heater coil 195, conducting bracket 196, bushing 175 which being grounded permits current to return to the battery via the ground connection. This circuit will cause the coil 195 to become hot.

Air under pressure will also flow from the passage 150 to the orifice 151 into and through passage 152 and thus over the fuel nozzle 165, thereby causing fuel to be lifted from the pipe 27 and nozzle 165 and sprayed

- into the combustion chamber 153. Some of this fuel spray will contact direct with the exposed end of the heating coil 195 and thereby absorb heat therefrom. Another portion of this spray will flow through passage 180 in the tube 178 and pass down through the passage 184^a contacting with the heating coil in said passage thereby absorbing heat, from thence this fuel mixture or spray will mingle with the other spray in the combustion chamber 153. The spray engaging or contacting with the heating coil will tend to cool the same and prevent excessive heating thereof.
- 15 The fuel mixture spray entering through the passage 152 into the combustion chamber 153 will enter through passages 180 and 181 into the chamber 184^a in which the heating coil 195 is positioned, thereby tending to cool said heating coil and consequently preventing excessive heating thereof.
- 20 The burning spray projects into the sleeve 157 where it unites with the combustion air entering through the distributing air holes 158 in order that complete combustion may take place whereby to heat any desired portion of the carburetor or engine, preferably the spray about the air intake of the carburetor or the manifold of the engine, both 25 of which are not shown in the present drawing.
- 25 As long as air under pressure flows through passage 150, orifice 151 and passage 152 into the combustion chamber 153, the fuel spray caused by such air flow will engage with the heating coil 195 and thus absorb heat therefrom to prevent excessive heating thereof. However, if the operator should stop the source of air pressure supply 30 and forget to break the circuit connections to the heating coil serious injury might result to said heating coil through the over-heating thereof and useless waste of electrical energy be caused.
- 35 40 To avoid over-heating the wire 187 is placed in thermal contact with the heating coil 195. The resistance of coil 195 is normally greater than coil 187, hence coil 195 will be heated to a greater degree than coil 187. Heat generated by coil 195 will be conducted to coil 187 to control the resistance thereof. Therefore, as the coil 195 is excessively heated coil 187 will be abnormally heated and as the temperature of coil 187 increases its electrical resistance will be increased to reduce the flow of current to coil 195. From this it may be seen that the temperature of coil 195 will be held substantially in a safe value. The protecting coil 45 50 55 60 65 70 75 80 85 90 95 100 105 110 115 120 125 130
- 195 is most advantageously located in the present invention, since it is located directly above the heating coil and in heat receiving relations to said heating coil and connected electrically in series therewith.
- 65 The present invention provides an easily assembled unit. In case of injury to the porcelain tube said tube may easily be removed as a unit from the bushing by removing the nut 182 and thus permitting replacement thereof. If the wire of the heating coil be injured the nut 182 may be removed which permits removal of the entire heating unit and thereby the spool 186, wire 187 and coil 195 may be readily removed for the purposes of replacement.
- 75 While the form of mechanism herein shown and described constitutes a preferred form of embodiment of the invention, it is to be understood that other forms might be adopted, all coming within the scope of the claims which follow.
- What I claim is as follows:
1. An electrical unit adapted for heating fuel comprising a plug, an insulating sleeve supported within the plug, a resistance element supported within said sleeve, and a heating coil suspended from said resistance element and connected with the plug.
  2. An electrical unit adapted for heating fuel comprising a plug, an insulating sleeve supported within the plug, a resistance element supported within said sleeve, and a heating coil suspended from said resistance element, having a portion extending outside the sleeve and having connection with the plug.
  3. An electrical device adapted for heating fuel, comprising a heating coil, and a protective device of normally lesser electrical resistance than the heating coil in direct thermal relation therewith for regulating the resistance of the circuit for conducting current to the coil.
  4. An electrical unit adapted to heat fuel comprising a plug, an insulating sleeve supported within the plug, a resistance element and a heating coil supported within said sleeve, said sleeve provided with ducts for ventilating the heating coil.
  5. An electrical unit adapted to heat fuel comprising a plug, and insulating sleeve supported within the plug, a resistance element supported within said sleeve, a heating coil suspended from said resistance element having a portion extending outside the sleeve and having connection with the plug, said sleeve being provided with ducts adjacent the heating coil for ventilating the coil.
  6. An electrical unit adapted to heat fuel comprising a plug, an insulating sleeve supported within the plug, said sleeve having a stepped bore providing a shoulder, a threaded spool supported by said shoulder, a resistance element mounted on said spool, and a heating coil attached to said resistance element located within the sleeve and having connection with the plug outside the sleeve.

7. An electrical unit adapted to heat fuel comprising a plug, an insulating sleeve supported within the plug, said sleeve having stepped bore providing a shoulder, a
5 threaded spool supported by said shoulder, a resistance element mounted on said spool, a heating coil attached to said resistance element and extending axially through the smaller bore and having connection with
10 said plug outside the sleeve, and means for ventilating the smaller bore.

8. Electrical apparatus for heating fuel, comprising in combination, an electrical heating coil and a protecting resistance in series therewith and in heat receiving relation thereto, the resistance having a relatively high temperature coefficient and an electrical resistance normally lower than the heating coil.

In testimony whereof I hereto affix my ¹⁵ ²⁰ signature.

JOHN H. HUNT.
